UNITED STATES PATENT OFFICE.

FRANS GEORG LILJENROTH, OF WESTERÄS, SWEDEN.

ELECTRIC MACHINE.

1,247,297.

Specification of Letters Patent. Application filed May 20, 1916. Serial No. 99,003.

Patented Nov. 20, 1917.

To all whom it may concern:

Be it known that I, FRANS GEORG LILJENROTH, a citizen of the Kingdom of Sweden, residing at Westeräs, Sweden, have invented 5 new and useful Improvements in Electric Machines, of which the following is a specification.

This invention relates to electric machines, particularly to such machines provided with 10 commutators, and the object of the invention is to so construct such commutators, that an increased resistance to discharges between the different bars be obtained.

The invention consists briefly in composing 15 the commutator of bars having longitudinal recesses located near to the limit surfaces of the insulating layers and extending in radial and axial directions.

In the accompanying drawing Figure 1 is 20 a fragmentary sectional view of a commutator constructed in the usual manner. Figs. 2 and 3 are fragmentary sectional views of commutators embodying this invention. Fig. 4 is a side-view of a commutator bar.

25 Referring to Fig. 1, 1 denotes the bars and 2 the insulating layers counter-sunk beneath the peripheral surface of the commutator. According to the principles of electric strength the presence of the insulating 30 layers 2, which consist of a material having a higher dielectric constant than the air, has for consequence, that disruptive discharges in the air field 3 situated close to the layer 2 take place at a tension lower than that 35 required under general circumstances for discharges through an air field of the same width as 3.

In order to prevent this inconvenience and to obtain an increased safety from discharges without increasing the thickness of 40 the insulating layers, the lateral surfaces of the commutator bars are provided with recesses 4 forming lateral grooves extending parallel to the axis of the commutator 45 placed at the outer limit surfaces or ends of the insulating layer in radial direction. By suitably sizing the recesses 4 it is obtained, that the discharge voltage above the insulating layer 2 becomes at least equal to 50 the discharge voltage of the air field 3.

These recesses or grooves 4 are cut into one side, Fig. 2, or both sides, Fig. 3, of each section and their edges nearest the axis of the commutator are slightly below the outer 55 peripheral edges of the insulating layers 2, which edges remain below the surface of the

commutator. In this manner the spaces between the sections at the surface of the commutator remain undiminished.

When the grooves 4 are formed in both 60 sides of each commutator section, as shown in Fig. 3, the grooves of adjacent sections coöperate to form wider grooves below the surface of the commutator into which the outer edge of the intervening insulating 65 layer 2 projects. This outer edge is below the surface of the commutator, so as not to be contacted by a brush trailing on the commutator, and is in alinement with a narrow air gap 6, of normal size, but below it. In 70 other words, the grooves of adjacent segments are symmetrical with respect to the edge of the insulation 2. Corresponding recesses 5 may also be effected at the inner limit surfaces of the insulating layer as well 75 as at the end surfaces in axial direction, as is shown in Fig. 4.

Said recesses may be located at one side only of the insulating layer, as in Fig. 2, or at both sides thereof, as in Fig. 3. 80

In Fig. 2 the inner, smaller ends of the commutator sections are beveled to form a V-shaped gap, as shown at 5. The bevel is made on the same side of the section as the groove 4. 85

In Fig. 3 these grooves are formed on the inner ends of the commutator segments by cutting the edges away to make them thinner, as by cutting a rabbet along opposite edges of each segment, and when assembled 90 form pockets or gaps 5^a into which the inner edges of the insulating layers project. Here also the rabbets of adjacent commutator segments are symmetrical with respect to the intervening insulation 2, as 95 shown.

The presence of the insulating layers 2, Fig. 1, of material having a higher dielectric constant than air, produces disruptive discharges in the air field at 3 close to the 100 layer 2, and at a tension lower than that required under general circumstances for discharges through an air field of the same width as 3.

By allowing the insulating layer to extend beyond the surface of the commutator this disadvantage can be avoided, but naturally such a structure cannot be used on the surface of the commutator on which the brushes trail. In order to obtain a proper 105 surface for the brushes the problem has been to obtain a properly dimensioned air gap 110

without having it of such large tangential width as to cause the brushes to vibrate. This I have done by the structures illustrated in Figs. 2 and 3, where the narrow air gap 6 is sufficiently small to prevent the vibration of the brushes, while at the groove 4 it is sufficiently wide to adequately weaken the electrical field.

Having now described my invention, what I claim as new and desire to secure by Letters Patent is:

1. A commutator comprising a plurality of metallic bars and insulating layers therebetween, said metallic bars having at their edges recesses forming grooves along the edge, the one lateral wall of each groove consisting of the portion of insulating layer adjacent to said edge, said insulating layer terminating inside the face of the commutator.

2. A commutator comprising a plurality of metallic bars and insulating layers therebetween, said metallic bars having at their peripheral edges undercut recesses forming grooves with ribs along the edge extending beyond the end of the insulation layers, the one lateral wall of each groove being formed by the adjacent insulating layer which terminates inside the face of the commutator.

3. A commutator comprising a plurality of metallic bars and insulating layers therebetween, said metallic bars spaced apart at their edges to form air gaps at the surface of the commutator, and recesses below the surface of the commutator wider than and communicating with said air gaps into which said layers project.

In testimony whereof I have signed my name.

FRANS GEORG LILJENROTH.
